UNITED STATES PATENT OFFICE.

ANDREW J. ALEXANDER AND HENRY H. SMITH, OF LAUREL, IOWA.

SHIPPING-CRATE.

1,176,332.

Specification of Letters Patent. Patented Mar. 21, 1916.

Application filed May 19, 1914. Serial No. 839,631.

To all whom it may concern:

Be it known that we, ANDREW J. ALEXANDER and HENRY H. SMITH, citizens of the United States, residing at Laurel, in the 5 county of Marshall and State of Iowa, have invented new and useful Improvements in Shipping-Crates, of which the following is a specification.

This invention relates to shipping crates 10 and more particularly to folding shipping crates, the principal object of the invention being to provide a simple and efficient device of this character which may be folded so as to occupy small space in return shipment or storage and which may be conveniently set up into operative position.

Further objects of the invention will appear as the following description is read in connection with the accompanying drawing, 20 which forms a part of this application, and in which:—

Figure 1 is a side elevation. Fig. 2 is an end view. Fig. 3 is a vertical section on the line 3—3 of Fig. 1. Fig. 4 is a longitudinal 25 sectional view on the line 4—4 of Fig. 2. Fig. 5 is a perspective view showing the box partially folded and with the top removed. Fig. 6 shows the crate fully collapsed with the top applied thereto.

30 Referring more particularly to the drawing, 1 represents the bottom of the device which has secured to its side edges the side or flange members 2 one of which is wider than the other for a purpose to be herein- 35 after described. These side members are secured permanently upon the bottom and have extending over the same and over the bottom, reinforcing members 3 which have their terminals provided with eyes 4 ar- 40 ranged in a line with the upper edges of the members 2. The end members are indicated at 5 and are provided on their lower edges with reinforcing bars 6 whose terminals project beyond the sides of the end 45 members into pivoting or hinging pintles 7 which are journaled in the flange members 2, as shown in Fig. 3. These end members are adapted, as shown in Fig. 5, to fold down upon the bottom and have projecting 50 from their upper ends locating pins 8, the

purpose of which will be presently described.

Hinged to the flange members 2 and adapted to abut against the end members are the movable or folding side members 9 55 and 10 both of which are provided with metallic reinforcing battens 11 terminating at one end into hooks 12 which engage the eyes or apertures 4 in the members 3. The end battens 11 have their terminals project- 60 ing in opposite directions, while the intermediate batten may have its terminal projecting in either direction. The opposite terminal of each batten is provided with a hinged extension so as to overhang the end 65 members and these extensions, indicated at 13, are provided with apertures 14 to engage the locating pins so as to hold the end members against movement when the device is set up. The top which is unconnected to 70 any portion of the crate consists of a cover portion 15 having flanged ends 16 provided with hooks 17 adapted to engage the eyes 18 on the end members 5 or the eyes 18' on the bottom. 75

To fold the crate the hooks 17 are disengaged from the eyes 18 on the end members and the top removed. The hinged extensions 13 of the battens 11 are then disengaged from the locating pins, so that the 80 end members may be folded inwardly upon the bottom. The side member 10 is then folded upon the end members and the side member 9 folded upon the side member 10. The top is then positioned upon the side 85 member 9 and the hooks 17 engaged with the eyes 18' on the bottom.

What is claimed is:—

A crate comprising a bottom having flanged side edges, U-shaped reinforcing 90 members carried by the bottom and terminally provided with eyes extending above the side flanges, side members, reinforcing strips carried by the side members and each terminating at one end in a laterally pro- 95 jecting hook loosely mounted in an eye on one of the U-shaped members, end members provided with space locating pins on the top edge thereof, and an extension hingedly connected with the remaining end of each 100

reinforcing strip on the side members and provided with an eye for receiving one of the pins on the end members whereby, the end members are held against movement 5 when in operative position, and a cover for the crate adapted to hold said extensions in pin engaging position.

Copies of this patent may be obtained for five cents each, by addressing the "Commissioner of Patents, Washington, D. C."

In testimony whereof we affix our signatures in presence of two witnesses.

ANDREW J. ALEXANDER.

HENRY H. SMITH.
